UNITED STATES PATENT OFFICE.

ERIK BERTAS AND ANDREW BERTAS, OF MINNEAPOLIS, MINNESOTA.

BUCKSAW.

Application filed April 25, 1923. Serial No. 634,647.

To all whom it may concern:

Be it known that we, ERIK BERTAS and ANDREW BERTAS, citizens of the United States, residing at Minneapolis, in the 5 county of Hennepin, and State of Minnesota, have invented certain new and useful Improvements in Bucksaws; and we do hereby declare the following to be a full, clear, and exact description of the invention, such as will enable others skilled in the 10 art to which it appertains to make and use the same.

Our invention relates to saws and more particularly to bucksaws and has for its object to improve the same in the several particulars hereinafter noted.

To the above end, the invention consists of the novel devices and combinations of devices hereinafter described and defined in 20 the claims.

In the accompanying drawings, which illustrate the invention, like characters indicate like parts throughout the several views.

25 Referring to the drawings:

Fig. 1 is a side elevation of the improved saw;

Fig. 2 is a view partly in elevation and partly in section illustrating the saw as 30 used in cutting off the ends of a plurality of boards set edgewise one upon the other;

Fig. 3 is a fragmentary perspective view of the front end portion of the saw frame and attached lever and main links;

35 Fig. 4 is a fragmentary view of the rear end portion of the saw frame and attached main and supplemental links and blade with some parts sectioned;

Fig. 5 is a fragmentary perspective view 40 of the rear end portion of the saw frame and attached main links; and

Fig. 6 is a perspective view of one of the pairs of supplemental links.

The numeral 7 indicates a saw blade held 45 in a frame which, as shown, is in the form of a bow comprising telescopically connected members 8 and 9 which permit said frame to be longitudinally adjusted to hold said blades of different lengths. It is important to note that the frame members 8 and 9 are of tubular structure and oval 50 shape in cross section which securely holds said members from turning in respect to each other. It will also be noted that the frame member 9 is of such vertical width 55 as to have a slight vertical swinging move-

ment within the frame member 8 and that said member 8, at its inner end, is slightly contracted to afford a fulcrum 10 on which said member 9 may swing.

To hold the members of the frames 8 and 9 in different telescoped relation, the frame member 9 is provided at its inner end with upstanding teeth 11 arranged to bite against the external surface of the frame member 8 under the tension of the saw blade 7. The front end portion of the frame member 8, in cross section, is formed on an expanded taper to afford a more convenient hand hold.

For attaching the saw blade 7 to the 70 frame, there is attached to the front end of said frame a lock lever 12 which carries a pair of main links 13, and at the rear end of said frame there is attached a pair of main links 14.

Pivoted to the free end of 75 each pair of main links 13 and 14 is a pair of supplemental links 15 and 16, respectively. The lock lever 12 is pivoted at 17 to the frame member 8 and is U-shaped in cross section so as to snugly fit around and 80

against the front edge portion of said frame member, as shown in Fig. 1. The lock lever 12 extends between the main links 13 which are connected thereto by pivots 18 that are radially offset from the 85 pivot 17. The other end portions of the main links 13 are contracted and then extended parallel to receive therebetween the supplemental links 15, which, as previously stated, are pivoted thereto. A stud 19 90

forms the pivot between the main links 13 and supplemental links 15, and which stud is rigidly secured to one of said main links and extends through a pair of aligned holes in the supplemental links 15, and a hole 20 95 in the other of said main links. The main links 13, at their pivots 18, are sufficiently loose to permit their other ends to be separated laterally to withdraw the stud 19 from the hole 20 and supplemental links 15 and 100 thereby release said supplemental links.

To draw the main links 13 toward each other onto the supplemental links 15 and thereby hold the stud 19 in the hole 20 to prevent lateral displacement of the supplemental links 15 from the main links 13, there is provided a double-headed pin 21 slidably mounted in longitudinally extended slots 22 in the main links 13. When the lock lever 12 is released and the main link 13 positioned as shown in Fig. 3, the pin 21 may be moved in the slots 22 toward the lever 12 110

and thereby release the main links 13 so that they may be spread apart to withdraw the stud 19 from the hole 20 and from the supplemental links 15. To hold the pin 21 in the 5 end of the slot 22, adjacent to the supplemental links 15, and thereby hold the main links 13 from spreading, the inner surface of the frame member 8, at its lower end, is beveled or formed with a cam 23, as shown 10 in Fig. 1. The supplemental links 15 are detachably secured to the saw blade 7 by a stud 24 rigidly secured to one of said links and arranged to extend through a hole in the respective end of said blade and a hole 25 in 15 the other of said supplemental links. When the supplemental links 15 are released from the main links 13 they may be laterally separated to release the saw blade 7.

The main links 14 extend within the lower 20 end of the frame member 9 through a longitudinal slot 26 and are secured to said member by a pivot 27. One of the main links 14 is provided with a rigid stud 28 arranged to enter a hole 29 in the other of said links by 25 a lateral movement to detachably hold the supplemental links 16 in the same manner that the main links 13 hold the supplemental links 15. The width of the slot 26 is such as to hold the main links 14 against lateral 30 separation with the stud 28 in the hole 29. To laterally separate the main links 14 and thereby release the supplemental links 16, said main links may be turned downward out of the slot 26 and into the open end of 35 the frame member 9, as shown in Fig. 4. In this position of the main links 14, the supplemental links 16 may be readily detached therefrom. Said supplemental links 16 are detachably attached to the respective ends of 40 the saw blade 7 in the same manner as the supplemental links 15 are attached thereto, and one of said links is provided with a rigid stud 30 arranged to extend through a hole in the saw blade 7 and a hole 31 in the 45 other of said links.

To direct the main links 14 into the slot 26 and thereby close said main links onto the supplemental links 16, the lower ends of the sides of the frame member 9, at the slot 26, 50 are beveled at 32, as shown in Fig. 5.

It is important to note that both pairs of supplemental links 15 and 16 are twisted to hold the saw blade 7 in a plane that is oblique to the plane of the frame. By thus holding the saw blade, the ends of boards, timbers or the like *x* placed as indicated in Fig. 2, may be easily sawed or their ends cut off, and at which time the frame extends oblique to the line of cut so that the same may 55 be freely operated and will not bend or turn the saw blade.

To attach the saw blade 7 to the frame, the members of said frame are first adjusted to the proper longitudinal length and the supplemental links 16 attached to the respective

end of said blade. Said supplemental links 16 are then inserted between the main links 14 while separated and extending through the open end of the frame member 9. The main links 14 are then closed onto the supplemental links 16, and the saw blade 7 and links 14 and 16 turned into a horizontal position. This movement of the saw blade 7 carries the main link 14 into the slot 26 which holds the same against lateral separation and thereby securely holds the main links 14 interlocked with the supplemental links 16 and said supplemental links 16 interlocked with the saw blade 7. The supplemental links 15 are then applied to the respective end of the saw blade 7, and said supplemental links attached to the main links 13, and at which time the lever 12 is in a released or depending position and the pin 21 in a retracted position to permit the main links 13 to be opened and then closed onto the supplemental links 15 to interlock the same therewith. The pin 21 is then projected in the slots 22 toward the saw blade 7 to hold the main links 13 interlocked with the supplemental links 15, and said supplemental links 15 interlocked with the saw blade 7. Finally the lock lever 12 is turned upward which carries the pivots 18 outward of the pivots 17 and places the saw blade 7 under tension, and in this position of the lock lever 12, the pivots 17 are above or beyond a dead center so as to hold said lock lever in an operative position, as shown in Fig. 1. The pin 21 is held by the cam 23 so that it cannot move in the slots 22 and thereby release the main links 13.

By removing the supplemental links 15 and 16, the saw blade may be attached to the main links 13 and 14 in the same manner that it is attached to the supplemental links, and which main links hold the saw blade 7 in the plane of the frame.

What we claim is:

1. In a bucksaw, the combination with a frame, of a saw blade, and means including main and supplemental links for attaching the saw blade to the frame, said supplemental links being twisted to hold the saw blade in a plane that is oblique to the plane of the frame.

2. In a bucksaw, the combination with a frame, of a saw blade, main links attached to the frame, and supplemental links detachably secured to the main links and having means for releasably holding the saw blade, said supplemental links being arranged to hold the saw blade in a plane that is oblique to the plane of the frame, said main links being adapted to hold the saw blade in the plane of the frame when the supplemental links are detached from the saw blade.

3. In a bucksaw, the combination with a frame, of a saw blade, a lever pivoted to

- one end of the frame, means for attaching one end of the saw blade to the other end of the frame, a pair of links pivoted to the lever at offset points with freedom for lateral separation, a stud on one of said links arranged to interlock with the other of said links for holding the respective end of the saw blade, said links being free for lateral separation to release the saw blade, said lever being movable from one position to another to place the saw blade under tension and release the same, and means held by the frame to prevent lateral separation of the links when the saw blade is under tension.
4. The structure defined in claim 3 in which the last mentioned means is carried by the links and arranged to be engaged by a cam surface on the frame and held in an operative position when the lever is moved to place the saw blade under tension.
5. In a bucksaw, the combination with a frame, of a saw blade, a lever pivoted to one end of the frame, means for attaching one end of the saw blade to the other end of the frame, a pair of main links pivoted to the lever at offset points, a pair of supplemental links releasably held by the main links, said supplemental links having separable interlocking engagement with the respective end of the saw blade and held from releasing by the main links, and means held by the frame to prevent the main links from releasing the supplemental links.
6. The structure defined in claim 3 in which the links are beyond a dead center when the lever is in a position to hold the saw blade under tension.
7. In a bucksaw, the combination with a frame, of a saw blade, a pair of main links pivoted within one end of the frame with freedom for lateral separation when in one position and held by a slot in the frame when in another position, a pair of supplemental links releasably held by the main links and having means for releasably holding one end of the saw blade, and means for attaching the other end of the saw blade to the other end of the frame.

In testimony whereof we affix our signatures.

ERIK BERTAS.
ANDREW BERTAS.
